UNITED STATES PATENT OFFICE.

HARVEY FELDMEIER, OF LITTLE FALLS, NEW YORK, ASSIGNOR TO D. H. BURRELL & CO., INC., OF LITTLE FALLS, NEW YORK.

RETURN BEND HEADER FOR PIPES.

Application filed January 3, 1922. Serial No. 526,830.

To all whom it may concern:

Be it known that I, HARVEY FELDMEIER, a citizen of the United States, residing at Little Falls, in the county of Herkimer and 5 State of New York, have invented a new and useful Improvement in Return Bend Headers for Pipes, of which the following is a specification.

My invention relates to improvements in 10 return bend headers or closures for pipes or tubes and particularly for the pipes or tubes used in apparatus for cooling or heating milk or other fluids.

One of the objects of my invention is to 15 provide a return bend header or closure for tubes of this character, which may be readily and conveniently applied to the adjacent tubes to form a return bend connection therebetween without disturbing or dis- 20 placing the tubes. Another object of my invention is to provide a return bend header which may be readily opened to permit the cleaning of the tubes themselves and to permit the cleaning of the header. Another 25 object of my invention is to provide a return bend header which will form a clear passage without obstructions or projections that can cause the lodgment of milk or other fluid passing therethrough; and also to improve 30 return bend headers in the other respects hereinafter described and set forth in the claims.

For the purpose of illustrating my invention I have shown one embodiment thereof 35 in the accompanying drawing in which:

Fig. 1 is a side elevation of a portion of a liquid cooler or heater showing an applica- 40 tion of my invention,

Fig. 2 is a longitudinal sectional view of a portion of a liquid cooler or heater and of the header,

Fig. 3 is an end view of the return bend header,

Fig. 4 is a detail section showing the cover 45 opened,

Fig. 5 is a detail section showing the manner of securing the tubes in the header, and

Fig. 6 is a perspective view of the header cover detached.

50 In the structure selected for showing an embodiment of my invention I have illustrated a portion of an apparatus for cooling or heating milk in which there is provided a series of inner flow tubes or passages 55 through which the milk is adapted to flow

and a series of outer flow tubes or passages surrounding the inner tubes and through which the cooling or heating liquid is adapted to flow, headers being arranged to connect or establish communication between 60 the adjacent ends of the inner tubes.

Referring specifically to the structure illustrated, the cooling or heating apparatus comprises a series of tubes as above described, arranged one above the other, and 65 to this end I provide a pair of oppositely disposed, upright manifold heads or headers 1 which support both the inner tubes 3 and the outer tubes 4 and provide return passages connecting the outer tubes to permit 70 the liquid to flow from one outer tube to the next. These flow passages of the heads 1 are divided by partitions 5 which subdivide the interior chambers of the heads in such manner that zig zag flow passages are 75 formed by the headers and the outer tubes through which the cooling liquid flows back and forth. The outer tubes 4 are connected with the headers 1 by stuffing boxes 6 arranged on the inner faces of the headers and 80 having therein suitable packing 7 secured in position by packing glands 8 which are screw threaded into the stuffing boxes 6 and are suitably fashioned to permit of the use 85 of a wrench thereon.

The inner tubes 3 extend through the heads 1 and are held in position in the heads and the surrounding openings tightly closed by stuffing boxes 9 formed on the outer faces of the heads opposite the stuffing boxes 6 90 and having arranged therein packing 10 held in position by packing glands 11.

The inner tubes project through the stuffing boxes 9 and the adjacent ends of two adjacent tubes are connected by a return 95 bend header so that the milk or other liquid flowing out of one tube will flow through the return bend header back into the next adjacent tube, thus taking a zig zag course throughout the series of tubes. When such 100 apparatus is used for handling milk it is desirable that the apparatus be kept thoroughly sterilized and that the apparatus and particularly the parts through which the milk passes be so arranged and constructed that the tubes and all channels through which the milk passes shall be readily accessible for inspection and cleaning. To this end each of the return bend headers through which the liquid passes is 110

so constructed that it may be readily opened without disassociating the parts thereof to permit not only the cleaning of the tubes themselves but to permit easy and thorough 5 cleaning of the return bend passage. In the structure illustrated whereby the above and other advantageous results may be obtained, I provide a return bend header comprising a base 12 and a cover 13. The base preferably 10 consists of an elongated casting having pipe receiving openings formed therein, each opening extending clear through the casting and forming a stuffing box 14 surrounding the inner pipe or tube 3. The stuffing box 15 is enlarged and internally screw threaded as at 15 and has a conical seat 16 surrounding the tube. Surrounding the tube and engaging against the conical seat 16 is a packing ring 17 formed preferably of ductile metal, such for instance as copper, which is forced against the seat 16 and thereby contracted into close gripping engagement with the end of the tube 3 by means of a screw threaded gland 15^a which is screwed 20 into the internal thread of the opening through which the tube passes. The gland is hexed or otherwise shaped to permit the application of a wrench for tightening it in position. 25 The base 12 is provided at its outer side with a cover seat 18 which surrounds the ends of the two inner tubes 3 and cooperates with a complementary seating portion on the cover 13 to form a continuous joint. 30 rounding the open ends of the two tubes, the base and cover forming an elongated chamber with which the pipes communicate and which provides a passage from one pipe to the other. As shown in the drawings, the cover seat 18 on the base is in the form of a raised annular rib or flange, and the cover has formed in its inner side an elongated recess 20 which together with the recess 19 formed in the base by the flange 35 18, constitute the return passage establishing communication between the two pipes or tubes. A suitable packing is employed between the complementary seating portions of the base and cover which insures a tight 40 joint between the cover and base, a packing gasket confined in a groove 21 in the edge of the cover being shown for this purpose. 45 The cover 13 is pivoted to a carrying arm 23, preferably by a pair of spaced lugs 22 50 on its outer face between which the arm is arranged and a pivot pin 24 extending through the lugs and arm. The arm 23 is hinged to the base 12, preferably between lugs 25 on the base, and at its free end is 55 bifurcated at 26 to receive a bolt 27 hinged at 28 to the base and provided with a wing nut 29 at its outer end to engage the bifurcated end of the swinging arm 22. By the 60 above mounting, due to the hinged connection with the swinging arm, the cover is 65

free to rock slightly and engage the flange 18 with uniform pressure at all points, while the hinged arm and bolt provide means whereby the cover may be securely and tightly clamped in position.

It will be observed that when the cover carrying arm 23 is released and raised, and the cover thereby removed, the entire interior of the coupling or header is exposed to permit access to the interior of the tubes 70 for sighting therethrough and the ready cleaning thereof. Furthermore, the return bend passage is formed by open-sided recesses 19 and 20 in the base and cover so that when the cover is opened all parts of 75 the connection are exposed and may be easily cleaned and sterilized and this without the disassociating of any of the parts thereof. This is desirable since it eliminates the possibility of dropping and injuring or losing 80 any of the parts. It will be noted also that by the provision of the stuffing boxes for connecting the return bend header to the tubes 3 these headers are readily detachable 85 from the ends of the tubes and may be quickly and easily removed for the purpose of 90 repair or renewal. This construction also enables the headers to be readily applied to coolers or heaters which are in use and in which it would be impracticable to properly 95 solder the headers in place.

While I have illustrated and described one embodiment of my invention it will be understood that my invention may be embodied in various forms and that various 100 modifications of the structure illustrated may be made without departing from the spirit of the invention as set forth in the appended claims.

Having thus described my invention, what 105 I claim as new and desire to secure by Letters Patent is:

1. A return header for connecting the ends of adjacent tubes, comprising a base having openings therethrough in which the 110 ends of the tubes are adapted to be secured, a cover for said base and cooperating therewith when the cover is in closed position on the base to form a return bend passage establishing communication between the ends 115 of said tubes, said cover being mounted on the base to move inwardly and outwardly toward and from the same substantially perpendicular to the plane of the cover-seat on the base for closing and opening said return bend passage, and means for releasably securing said cover in closed position.

2. A return header for connecting the ends of adjacent tubes, comprising a base having openings therethrough in which the 125 ends of the tubes are adapted to be secured, a movable cover for said base and cooperating therewith when the cover is in closed position on the base to form a return bend passage communicating with the ends of 130

- said tubes, an arm hinged to said base and a hinge connection between said cover and said arm to permit the bodily separation of said cover from said base in a direction substantially perpendicular to the plane of the cover-seat on the base, and means cooperating with said arm for clamping said cover against said base.
3. A return header for connecting the ends of adjacent tubes, comprising a base having openings therethrough in which the ends of the tubes are adapted to be secured, a cover for said base cooperating therewith when the cover is in closed position on the base to form a return passage establishing communication between the ends of said tubes, said cover and base having opposed seating portions which extend uninterruptedly around the ends of said tubes, and said cover being mounted on said base to move inwardly and outwardly toward and from the latter substantially perpendicularly to the plane of the cover seat on the base for clos-
- ing and opening said return passage, a packing between said seating portions of the base and cover, and means for releasably securing said cover in closed position.
4. A return header for connecting the adjacent ends of tubes, comprising a base having openings extending therethrough for the reception of said tubes, a rib on the outer side of said base surrounding said openings and forming a single cavity connecting with both openings, and a cover for said base having a recess in its inner side and at its edge seating on said rib to form between said base and cover a return bend passage communicating with the ends of the tubes, said cover being mounted on said base to move substantially perpendicularly toward and from the plane of said rib for closing and opening said passage, and means for releasably clamping said cover against said rib.

HARVEY FELDMEIER
